JOSEPH W. GAMBLE, OF PHILADELPHIA, PENNSYLVANIA, ASSIGNOR TO HARRISON SAFETY BOILER WORKS, OF PHILADELPHIA, PENNSYLVANIA, A CORPORATION OF PENNSYLVANIA.

WATER-HEATING APPARATUS.

1,101,428.

Specification of Letters Patent. Patented June 23, 1914.

Application filed July 31, 1909. Serial No. 510,623.

To all whom it may concern:

Be it known that I, JOSEPH W. GAMBLE, a citizen of the United States, residing at Philadelphia, in the county of Philadelphia and State of Pennsylvania, have invented certain new and useful Improvements in Water-Heating Apparatus, of which the following is a specification.

This invention relates to apparatus for heating water for use in the boilers of steam-engines or in heating systems, and it is directed particularly to the provision of a water-heating apparatus to be installed in or adjacent to a locomotive round-house to supply water for washing and filling the boilers of the locomotives.

The object of the invention is to provide an apparatus for heating water which is of special utility in round-house work, which is reliable and efficient in operation, and which is economical in that it is arranged to utilize the heat in either or both the steam and water blown off from a locomotive in emptying the latter to heat the water which is employed for washing and filling.

In filling a locomotive boiler, it is desirable to use water at or near a temperature of 212° Fahrenheit, in order to reduce as much as possible the time during which a locomotive is out of service, but such water is too hot for use by the workmen in washing the boiler. However, the washing operation is more readily effected using water which has been heated somewhat, and therefore water at a temperature of about 130° Fahrenheit is usually employed in washing.

In accordance with the invention, two supplies of water are maintained, one supply for use in washing the boilers of the locomotives and one for use in filling the boilers.

The invention involves the use of two storage-tanks with pipes for supplying water thereto and drawing water therefrom, heating devices whereby the water stored in the two tanks is heated, and devices which operate automatically to maintain the water in one of the tanks at the temperature desired for the water employed in washing the boilers of the locomotives. In order to secure economy in operation, the heating of the water in the two storage-tanks is effected by either or both the steam and water drawn

off from the locomotive in emptying the latter, both the steam and water being introduced into the filling water when both are substantially free from impurities and the steam only being so employed when the water contains such impurities as to make it unsuitable for further use in a boiler; in the latter case, the blow-off from a locomotive is carried through a suitable steam-trap and if desirable a separator may be employed through which the steam is carried. Preferably the steam or the steam and water blown off from the locomotive are carried directly into the tank for the filling-water, so as to heat the water therein and the steam then passes through a suitable pipe to a heater provided for heating the washing-water prior to or after its admission to the storage-tank for the washing-water. The water in this tank is constantly maintained at a predetermined temperature, and for this purpose automatic devices are employed for controlling the operation of the heater to heat water which is admitted to this tank. In the preferred form of the invention, this automatic means includes a thermostat extending into the storage-tank for the washing-water and controlling a valve in the pipe employed for carrying steam to the heater. To further insure the maintenance of the desired temperature of the washing-water in this storage-tank, a circulating system is provided, whereby water is circulated from the storage-tank through the heater, and preferably the circulation of water in this system is also governed by the temperature of the water within the tank. For effecting this circulation of the water, a pump may be employed, whose speed is automatically controlled, or the heater may be arranged to act as an injector; in which latter case the provision of a circulating pump is avoided. The heater for the water admitted to the tank for the washing-water and for the water circulated as above described may be of the type employing trays or a spray, as is usual in water-heaters, or this heater may be in the form of a jet-condenser; the latter construction is that which I prefer to utilize, but the type of heater employing the trays or the water-spray may be employed as desired, as may also the direct injection of the steam into the storage-tank.

I have illustrated the preferred embodiment of my invention in the accompanying drawings, in which—

Figure 1 shows the apparatus employed, 5 diagrammatically, and Fig. 2 is a sectional view illustrating the heater.

Referring to these drawings, 1 indicates a storage-tank, in which is stored the water for filling the boilers of the locomotives, 10 and 2 indicates a second tank for the storage of the washing-water. Cold water is admitted to the storage-tank 1 through a cold water supply pipe 3, and this pipe has a valve 4 therein which is operated automatically by a float 5 in the tank 1, so that 15 the level of the water in tank 1 is maintained substantially constant. The water for filling a locomotive is drawn from the tank 1 through a pipe 6 connected to the upper portion of the tank by a pump 7 which forces the water through a pipe 8 having a suitable valve 9 therein. In heating water in tank 1, I utilize the heat in the steam or the steam and water blown off from 20 a locomotive in emptying the latter, and this may be done in any suitable manner. In the drawings, I have shown a pipe 10 extending along the side of the tank 1 near the bottom thereof, and a plurality of connections 11 distributed along the length of 25 the pipe 10 and entering the tank. If the water is sufficiently free from impurities to permit of its further use in a boiler, both the water and the steam exhausted from the 30 boiler in emptying the latter are carried through pipe 10 and into the tank 1. If, on the other hand, the water from a boiler contains such impurities as to make it unsuitable for further use, the water and steam 35 are carried to a suitable trap, which permits the steam only to pass through the pipe 10 to the tank 1, and if desired a separator may be provided in the steam passage. If both the water and steam are admitted to tank 1, 40 the latter is of such capacity as to enable it to receive this blow-off water in addition to the supply of water already therein admitted through the pipe 3. Within the tank 1, the steam rises through the water in the 45 tank and more or less of it is condensed and imparts its heat to the water in the tank. The steam which is not condensed rises to the top of the tank and passes out through a pipe 12 connected to the tank. In this 50 pipe is a relief-valve 13, so that if the pressure within the tank rises above a predetermined point the pressure will be relieved by exhausting a portion of the steam to the atmosphere.

60 A pipe 14 is connected to the pipe 12, so as to carry the steam from the tank 1 to a water-heater 15, which is either mounted within the tank 2 or connected to the tank by a pipe 16, as shown in Fig. 1. The 65 heater 15 may be of any suitable construc-

tion, but that which I prefer to employ is one similar to a jet-condenser, as shown in Fig. 2. Cold water is supplied to the heater through a pipe 17, having a valve 18 therein, which is automatically opened and closed 70 by a float 19 within the tank 2, so as to maintain the desired level of water within the tank. The cold water supplied by pipe 17 enters the heater at the top thereof through a suitable nozzle 20, and the steam 75 carried to the heater by the pipe 14 enters the heater at the side through the port 21, so that the steam flows around the nozzle 20 and becomes mingled with the water supplied to the heater. 80

In the pipe 14 is a diaphragm-valve 22, which is automatically controlled so as to open and close in response to changes of the conditions within the tank 2. For effecting this control of valve 22, I have provided a 85 thermostat 23 mounted upon the tank 2 and extending within the same; this thermostat is connected to the diaphragm-valve 22 by a pipe 24, so that when the temperature of the water within tank 2 falls below that desired for the washing-water, the valve 22 will be opened more or less, so as to admit steam from the tank 1 through pipe 14 to the heater 15, where the steam mingling with the water passing through the heater 90 will raise the temperature of the water to that desired. In order to facilitate the maintenance of this desired temperature of the water in tank 2, a circulating system is provided, whereby the water stored in tank 95 100 2 is circulated through the heater 15. This circulating system includes a pipe 25 connected to the bottom of the tank 2, and a pipe 26 connected to the pipe 17 which leads to the heater 15. For circulating the water, 105 through these pipes, the heater 15, when in the form of a jet-condenser, may be constructed to act as an injector, so as to maintain the circulation of the water through pipes 25 and 26, but if it is not desired to 110 employ this means for circulating the water or if the conditions under which the apparatus is employed do not permit of it, a pump 115 27 may be provided, to which the pipes 25 and 26 are connected and which is operated to maintain the desired circulation. This pump may be supplied with steam from any suitable source, but in order to secure economy of operation the steam for operating the pump may be drawn from the pipe 14 120 which carries the steam from the tank 1 to the heater 15. For this purpose, a pipe 28 is provided, leading to the pump 27 from a point in the pipe 14 between the diaphragm-valve 22 and the heater 15; and a back-pressure valve 29 is inserted in the pipe 14 125 between the heater 15 and the point of connection of the pipe 28 to the pipe 14. The valve 29 is so set that it will not open until the amount of steam admitted to the pipe 130

14 is in excess of that required to operate the pump 27, but when the supply of steam does exceed this amount the valve will open, so as to admit the excess of steam to the heater 15. 5 The diaphragm-valve 22 may be so arranged that it will never close entirely, so that at all times sufficient steam is allowed to pass through the pipe 28 to keep the pump 27 in motion.

10 The operation of the apparatus constructed as above described is as follows:— A constant supply of water for filling the boilers of the locomotives is maintained within tank 1 by the pipe 3, and this water 15 is heated to a temperature approaching 212° Fahrenheit by the steam or the steam and water admitted to the tank through the pipe 10. The excess of steam over that required for keeping the water in tank 1 at this temperature passes to the top of the tank and then through the pipes 12 and 14. If the water within tank 2 is at the temperature desired for the washing-water, that is, at about 130° Fahrenheit, the thermostat 23 20 will keep the diaphragm-valve 22 closed, so as not to permit steam to pass, or keep it so nearly closed that the steam passing valve 22 will not be sufficient to open valve 29 and will merely serve to keep the pump 27 in motion. If the temperature of the water in tank 2 falls below this, however, the thermostat 23 will operate to open the valve 22. Steam then passes through the pipes 14 and 28 to the pump 27, and the latter starts or 25 resumes its normal speed, so as to draw water from the bottom of the tank 2 and force it through the pipe 26 to the heater 15. If the steam supplied to and passing through the pipe 14 is more than sufficient to operate 30 pump 27, it will open the valve 29 and pass into the heater 15, wherein it will become mingled with the water brought to the heater by the pipe 26 of the circulating system and by the cold water supply pipe 17 (when the 35 valve 18 is opened), so as to heat this water and thus bring the temperature of the water in the tank 2 up to the desired point. The supply of water for washing the boilers of the locomotives is thus maintained at the 40 proper temperature at all times by mechanism which operates automatically to raise the temperature of the water whenever it falls below that desired, and this water may be drawn off by a suitable pump or by gravity through a pipe 30 connected to the tank 2.

Instead of the form of heater for the filling water herein shown and described whereby the steam for heating is carried into the bottom of the tank and allowed to pass upwardly through the water, other forms of heaters may be employed and good results obtained, as for instance, a heater employing means for spraying the water into the steam or trays over which the water flows while 45 steam is rising through them. Furthermore,

it will be apparent that the relief valve 13 should be so set as to open only on a pressure higher than that on which the valve 29 opens; this valve 13 being employed merely as a protective device.

70 While I have illustrated in the accompanying drawings and described above the construction of the apparatus which I prefer to employ in practising my invention, I wish it understood that this construction may be modified in the respects to which I have referred and in many others while still embodying the features of my invention. Such modifications, therefore, I consider as coming within the scope of my invention and I aim to cover them by the terms of the claims appended hereto.

75 Having now described my invention, what I claim as new therein and desire to secure by Letters Patent is as follows:—

80 1. The combination of two water storage tanks, pipes for withdrawing water therefrom, means for carrying steam to one of said tanks to heat the water therein, a heater for the water to be stored in the second tank, a pipe connecting the first tank with the heater for carrying steam to the heater, an automatically operated valve in said pipe, a pipe connecting the heater to said second tank, and means for supplying water 85 to the heater, substantially as set forth.

90 2. The combination of two water storage tanks, a supply-pipe for admitting water to one of said tanks, means for carrying steam to said tank to heat the water therein, a heater for the water to be stored in the second tank, a pipe connecting the first tank to said heater for carrying steam to the heater, a valve in said pipe, a thermostat 95 extending within said second tank and operating said valve, a pipe connecting the heater to the second tank, means for supplying water to the heater, and means for withdrawing water from said tanks, substantially as set forth.

100 3. The combination of two water storage tanks, a supply-pipe for admitting water to one of said tanks, means for carrying steam to said tank to heat the water therein, a heater connected to the second tank for heating the water to be stored in the second tank, a pipe connecting the first tank with said heater, a valve in said pipe, a thermostat projecting into said second tank and automatically operating said valve, and means for maintaining a circulation of water from said second tank through said heater, substantially as set forth.

110 4. The combination of two water storage tanks, means for admitting water to one of said tanks, means for carrying steam to said tank to heat the water therein, a heater connected to the second tank for heating the water to be stored in the second tank, a pipe connecting the first tank with the 115

heater for carrying steam to the heater, a valve in said pipe, a thermostat projecting in the second tank and controlling said valve, means including a pump for maintaining a circulation of the water in the second tank through the heater, and a pipe for supplying steam to the pump from the said pipe connecting the first tank to the heater, substantially as set forth.

5. The combination of two water storage tanks, a supply-pipe for admitting water to one of said tanks, means for carrying steam to said tank to heat the water therein, a heater connected to the second tank for heating the water to be stored in the second tank, a pipe connecting the first tank with said heater, a valve in said pipe, a thermo-

stat extending within said second tank and operating said valve, means including a pump for circulating water from said second tank through said heater, a pipe connecting the pump to said pipe at a point in the latter between said heater and said valve, and a second valve in the pipe connecting the first tank and the heater located 25 between the heater and the point of connection of said pipes, substantially as set forth.

This specification signed and witnessed this 29th day of July, 1909.

It is hereby certified that the assignee in Letters Patent No. 1,101,428, granted June 23, 1914, upon the application of Joseph W. Gamble, of Philadelphia, Pennsylvania, for an improvement in "Water-Heating Apparatus," was erroneously described and specified as "a corporation of Pennsylvania," whereas it should have been described and specified as *a copartnership of Pennsylvania*; and an error appears in the printed specification requiring correction as follows: Page 1, line 53, for the word "drawn" read *blown*; and that the said Letters Patent should be read with these corrections therein that the same may conform to the record of the case in the Patent Office.

Signed and sealed this 14th day of July, A. D., 1914.
